Primary Examiner — Holly E Thurman*Assistant Examiner* — Bobby W Jones, II(74) *Attorney, Agent, or Firm* — Goldstein Law Offices, P.C.(57) **CLAIM**

The ornamental design for a faucet filter, as shown and described.

DESCRIPTION

FIG. 1 is a perspective view of a faucet filter in accordance with the present invention;

FIG. 2 is a top plan elevation view thereof;

FIG. 3 is a bottom plan elevation view thereof;

FIG. 4 is a front elevation view thereof;

FIG. 5 is a rear elevation view thereof;

FIG. 6 is a left side elevation view thereof; and,

FIG. 7 is a right side elevation view thereof.

The broken lines in the drawings depict portions of the faucet filter that form no part of the claimed design.
